DOOR STOP

Irvine Kimmel, Miami Beach, Fla., assignor to Endure-A-Lifetime Products, Inc., Miami, Fla., a corporation of Florida

Continuation of design applications Ser. No. 5,185 and Ser. No. 5,186, Dec. 27, 1966. This application June 14, 1967, Ser. No. 8,015

Term of patent 14 years

(Cl. D10—7)

FIG. 2

FIG. 1

FIG. 3

FIG. 4

FIG. 5

FIG. 7

FIG. 6

FIG. 8

FIG. 9

FIG. 10

FIGURE 1 is a side elevational view of an extruded door stop showing my new design.

FIGURE 2 is a rear elevational view.

FIGURE 3 is a front elevational view.

FIGURES 4 and 5 are top and bottom plan views, respectively.

FIGURE 6 is a side elevational view of a door stop showing an alternate design thereof.

FIGURES 7 and 8 are rear and front elevational views, respectively.

FIGURES 9 and 10 are top and bottom plan views, respectively.

This application is a continuation of design applications 5,185 and 5,186 filed Dec. 27, 1966, now abandoned.

I claim:

The ornamental design for a door stop, substantially as shown.
